FIG. 2.

FIG. 1.

FIG. 3.

To all whom it may concern:

Be it known that I, Sophie Frydlander, have invented a new, original, and ornamental Design for a Combined Bottle and Box Therefor, of which the following is a specification, reference being had to the accompanying drawing, forming a part hereof.

Fig. 1 is a side elevational view of a combined bottle and box therefor showing my new design.

Fig. 2 is a front elevational view thereof viewed in the plane of the line 2—2 of Fig. 1, and

Fig. 3 is a side elevational view of the bottle portion removed from the box portion thereof.

The dominant features of my design reside in the portions shown in full lines.

I claim:

The ornamental design for a combined bottle and box therefor, as shown and described.
